UNITED STATES PATENT OFFICE.

JOHN NELSON DUNDAS HEENAN, OF CHAPEL WALKS, MANCHESTER, ENGLAND,
ASSIGNOR TO HEENAN & FROUDE LIMITED, OF MANCHESTER, ENGLAND.

SUPERHEATER FOR LOCOMOTIVE, MARINE, AND OTHER TUBULAR BOILERS.

1,227,435.

Specification of Letters Patent.

Patented May 22, 1917.

Application filed May 12, 1916. Serial No. 97,160.

To all whom it may concern:

Be it known that I, JOHN NELSON DUNDAS HEENAN, a British subject, residing at Chapel Walks, city of Manchester, England, have invented certain new and useful Improvements in Superheaters for Locomotive, Marine, and other Tubular Boilers, of which the following is a specification.

This invention relates to superheaters for locomotive, marine and other tubular boilers in which two concentric steam tubes are inserted in the fire tubes and connected to steam headers in the smoke box.

The invention consists essentially in the particular construction and disposition comprising an independent connection box separately fitted to the end of each superheater element and independent tubes connecting the boxes to the steam headers, or in series to one another.

The invention will be fully described with reference to the accompanying drawings.

Figure 1. is a front elevation of a battery of steam superheaters with some of the inlet and outlet steam pipes broken away.

Fig. 2. is a longitudinal section through steam headers and three of the boiler tubes showing the disposition of the connections of four elements of the superheaters.

Fig. 3. is a longitudinal sectional elevation of one element of the superheater.

Fig. 4. is a transverse section through boiler tube showing superheater element in position.

Fig. 5. is a transverse section of connecting box.

The superheater tubes A A' are of ordinary construction or they may have ribs or gills a as in the specification of U. S. Patent No. 1070115, and are fitted into the boiler tubes B. And the inlet and outlet steam headers C C' are preferably placed transversely across the end of the boiler.

Each tube A is fitted at its outer end to a separate and independent connection box D through which the steam enters and leaves the superheater tubes A A'.

The connection box D is constructed with a through passage longitudinally and an interior annular chamber d into which an inlet port or passage d' enters at right angles and is fitted with two loose flanges E E' by which the inlet steam pipes e and outlet pipes e' or e^2 are attached to each connection box.

The external superheater tube A is screwed or expanded into the rear side of its connection box D connecting with or opening into the central or annular chamber d and the internal or return superheater tube A' is passed through the connection box and is screwed or expanded into the front end of the through passage therein thereby joining the two tubes A A' into a single superheater element. The outer ends of the two tubes A and A' are thus connected, the tube A with the inlet steam pipe e through the annular steam chamber d and passage d' and the tube A' with the outlet steam pipe e' or e^2 the opening into 70 which is coincident with the through passage of the connection box.

The joints for the inlet and outlet steam pipes e , e' or e^2 are formed by swaging or forming a flange e^3 around the end of each pipe and securing the flange to the face of the connection box D by a loose flange or plate E or E' placed over the tube and bolted to the connection box with or without a gasket or other packing.

Each inlet steam pipe e may lead direct from the inlet steam header C to a connection box D and each outlet steam pipe e' may be connected direct to the outlet steam header C'.

I at present prefer however to couple two or more connection boxes D and elements of the steam superheater together in series they being shown coupled together in pairs with the outlet steam pipe e^2 of the first 90 forming the inlet steam pipe of the second the first one being connected with the inlet steam header C by the inlet steam pipe e and the second one being connected with the outlet steam header C' by the outlet steam pipe e' . Any desired number of the elements may thus be connected in series.

What I claim as my invention and desire to protect by Letters Patent is:—

1. In a superheater of the class specified, 100 the combination with boiler tubes, of superheater tubes extending into the boiler tubes and of less diameter than the latter, and an independent connection box for each superheater tube, each connection box being constructed with a through longitudinal passage and interior annular chamber provided with an inlet port communicating with the annular chamber in planes at right angles to the superheater tube and also provided 110

with an outlet port, inlet and outlet pipes having terminals fitted over the inlet and outlet ports, and securing devices loosely surrounding and engaging the terminals of 5 the inlet and outlet pipes and connected to the box.

2. In a superheater of the class specified, the combination with boiler tubes each having a superheating tube therein, of a separate and independent connection box for 10 each superheating element, said box being provided with inlet and outlet ports at angles to each other, inlet and outlet pipes having inner flanged ends placed against 15 the connection box over the inlet and outlet ports, and plates loosely surrounding the inlet and outlet pipes and engaging the flanges of the said pipes, the said plates being secured to the connection box.
- 20 3. In a superheater of the class specified,

the combination with boiler tubes, superheater tubes mounted therein and inlet and outlet steam headers, of separate and independent connection boxes for the superheater tubes, each tube being connected to 25 a box, the connection boxes having passages therethrough and inlet and outlet ports opening into different portions of these passages, and independent inlet and outlet pipe connections between the inlet 30 and outlet headers and each box.

Dated this 19th day of April, 1916.

In testimony whereof I have hereunto set my hand in presence of two subscribing witnesses.

JOHN NELSON DUNDAS HEENAN.
